HOLDER FOR AMUSEMENT DEVICE
Max J. Ruderian, 545 Hanley Ave., Los Angeles, Calif.
Filed Oct. 25, 1962, Ser. No. 233,088
1 Claim. (Cl. 224—5)

This invention relates generally to supporting devices and more particularly to a novel holder for an amusement device to enable suspending of the device from a portion of a person's clothing.

For purposes of illustrating the present invention, the holder will be described in conjunction with the carrying of a "Yo-Yo." It should be understood, however, that the principles are applicable to other similar types of amusement devices.

The "Yo-Yo" is a well known toy and still enjoys considerable popularity. Generally, the "Yo-Yo" is made up of a pair of rotatable members secured together by a central shaft about which a string may be wound. This construction does not lend itself to easy carrying about. Thus, the device is somewhat bulky to be carried directly in a child's pocket and yet the child does not always wish to hold the "Yo-Yo" in his hand.

With the above in mind, it is a primary object of this invention to provide a very simple holder particularly adaptable for use with a "Yo-Yo" to the end that a person such as a child may readily carry the "Yo-Yo" about and yet have it instantly available for use.

More particularly, it is an object to provide a novel holder for a "Yo-Yo" which may be extremely economically manufactured so that if sold with a conventional "Yo-Yo," the overall price will not be appreciably greater than that of the "Yo-Yo" itself.

Briefly, these and other objects and advantages of this invention are attained by providing a holder for a "Yo-Yo" adapted to be received between the rotatable members of the "Yo-Yo" to cradle a portion of the central shaft extending between the members. With this arrangement, the rotatable members extend on either side of the cradling portion of the holder and thus the "Yo-Yo" is securely held. Another portion of the member terminates in suitable means for securing the same to a portion of a person's clothing.

In its preferred embodiment, the holder is in the form of a stamping of general S-shape, the upper portion of the S-shape defining a hook for securing to a portion of a person's clothing and the lower portion of the S-shape defining a reversely directed hook adapted to cradle the shaft between the rotatable members comprising the "Yo-Yo." Since a simple stamping is provided, the holder may be very economically manufactured.

A better understanding of the invention will be had by now referring to the preferred embodiment thereof as illustrated in the accompanying drawings, in which:

FIGURE 1 is a front elevational view of the holder of this invention showing the same as used for carrying about a "Yo-Yo";

FIGURE 2 is an end elevational view taken generally in the direction of the arrows 2—2 of FIGURE 1; and,

FIGURE 3 is a front elevational view of the holder itself without the "Yo-Yo."

Referring first to FIGURE 1, the holder comprises a generally S-shaped stamping 10 having an upper hook portion 11 and a lower hook portion 12. These hook portions may be defined by cutouts as shown to provide

2

the general S-shape. As shown, the upper hook portion 11 is adapted to be secured to a portion of a person's clothing such as a stay 13 for the person's belt 14. The lower hook portion in turn defines a cradle structure 5 for cradling the central shaft 15 of the "Yo-Yo."

With particular reference to FIGURE 2, it will be noted that the central shaft 15 secures together first and second rotatable members 16 and 17 defining the "Yo-Yo." A string adapted to be wound about the shaft 15 is illustrated at 18. It will be noted that the thickness "d" of the stamping 10 is less than the separation distance "D" between the rotatable members 16 and 17 as measured axially along the central shaft 15. Thus, the rotatable members 16 and 17 may extend downwardly 10 on either side of the lower hook-shape portion 12 of the stamping 10 so that the central shaft 15 is cradled within the hook portion 12 as illustrated in the dotted lines of FIGURE 1.

FIGURE 3 illustrates clearly the stamping 10 itself 20 wherein the S-shape structure is clear. The stamping could be made symmetrical about a transverse horizontal axis of desired so that either the hook portion 11 or the hook portion 12 could be employed to cradle the central shaft of the "Yo-Yo."

It should be understood that while the hook portion 11 has been illustrated as being secured to the stay 13 of a person's belt 14, the hook portion could be hooked directly over the belt or even to the edge of a person's pocket.

Further, it should be understood that since the holder 30 constitutes an integral stamping, it may be stamped out in large quantities extremely economically. Thus, if sold with the "Yo-Yo" itself, the overall price will not be appreciably greater than the price of the "Yo-Yo" alone.

While only the one particular embodiment of the invention has been shown and described, it will be understood that the principles of the holder may be employed even with slightly different shaped structures from that specifically shown in the drawings. The invention is 40 therefore not to be thought of as limited to the exact embodiment set forth merely for illustrative purposes.

What is claimed is:

A holder for an amusement device of the type comprising rotatable members secured together by a central shaft with a string adapted to be wound thereabout, said holder comprising: an integral stamping in the form of a flat sheet of thicknesses less than the distance between said rotatable members as measured along said shaft, said sheet having cut-out portions defining an upper hook portion adapted to be secured to a portion of a person's clothes and a lower hook portion defining a cradle for receiving said central shaft so that said members lie on either side of said lower hook portion to engage opposite sides of said sheet, the plane of said upper and lower hook portions lying in the plane of said sheet whereby said amusement device may be carried by said holder.
